SYNCHRONIZING SYSTEM

Mark B. Kerr, Grasmere, N. Y., assignor to International Communications Laboratories, Inc., Newark, N. J., a corporation of New York

Application December 31, 1931
Serial No. 584,121

9 Claims. (Cl. 178—53)

My invention relates to phase correction of two remotely disposed rotating members, and more particularly to synchronous telegraph or signalling systems.

The object of my invention is to provide simple and efficient means for keeping the remotely disposed members in phase with each other.

Telegraph systems such as that herein illustrated and described comprise rotating distributors remotely disposed with respect to each other and connected by a signalling conductor in which is disposed a polarized relay responsive to signals from the transmitting station. The signals transmitted are composed of spacing or positive impulses and marking or negative impulses.

The corrector mechanism comprises control relays initially controlled by the operation of the polarized relay when responding to the transmitted impulses. These control relays are then controlled in sequence by cams associated with the distributor mechanism.

The co-operation between the control relays and the cams eliminates the so-called "dead spot" so correction can take place at any period during the rotation of the distributor.

In adjusting the speed of a distributor with respect to the line signals, it is the usual practice to listen to the operation of the corrector and count the number of times the corrector magnet armature operates per minute, or to introduce a visual indication of the magnet operations.

I have arranged the circuit so that the corrector magnet is only energized for a fractional part of the revolution of the distributor, and the armature will operate as many times as the starwheel on the distributor is engaged with the correcting pin. There will thus be no difficulty in counting the number of corrections per minute.

My invention is illustrated in the accompanying drawings wherein:

Fig. 1 shows the apparatus and circuits of the corrector; and

Fig. 2 is a modification of Fig. 1.

Referring to Fig. 1, a drive shaft 45 for the distributor driven by means not shown carries a fly wheel 50 and a freely rotating brush carrier 47. The brush carrier has a gear wheel 48 formed integral therewith, which meshes with a pinion 39 secured to a short shaft 40 which is journaled in a control disc 41 operatively secured to shaft 45 by any suitable means,

such as pin 42. The other end of the shaft 40 has a starwheel 46 secured thereto which is prevented from rotating by a spring actuated detent roller 49 carried by control disc 41. The discs C1 and C2 are mounted upon shaft 45 and rotate therewith for controlling contacts 12, 13 and 22, 23, respectively.

A polarized line relay is shown at 2. The tongue of relay 2 follows the received line signals. When the tongue of relay 2 is resting against its spacing contact S, the condenser 3 will be discharged through resistance 4. When a marking signal is received, the tongue of relay 2 will move over to the marking contact M and the condenser 3 will be charged from battery 5. The charging current for condenser 3 will flow through the windings of locking relay 6. If the brush 7 is in proper phase relation with the received signals, then brush 7 will be on the B segments at the instant the tongue of relay 2 arrives at its marking contact, and the charging circuit of condenser 3 will be as follows: from battery 5, through condenser 3, marking contact M, winding 8 and winding 9 of relays 6, segment B, brush 7, and thence through solid ring 10 to ground. It should be noted that the charging impulse goes through windings 8 and 9 in series and that these windings are connected in opposition. Since windings 8 and 9 have an equal number of turns, it will be apparent that the armature 31 of relay 6 will not be operated. The resistance of windings 8 and 9, however, limits the charging current of condenser 3 and thereby prevents damage to the contacts of relay 2 or the distributor segments and brushes. When the brush 7 is out of phase with the received signal, the brush will be on the A segment at the instant that the tongue of relay 2 arrives at its marking contact.

The path of the charging impulse of condenser 3 will be as follows: from battery 5, through condenser 3, contact M, winding 8, segment A, brush 7, solid ring 10, and thence to ground. Since the charging current, in this case, passes through only one winding of locking relay 6, the armature 31 will be attracted and the relay will lock up.

When the need for correction occurs, locking relay 6 will lock itself up through its locking winding 11, and a circuit to ground is provided in two different ways. One is through contacts 22 and 23 controlled by cam C2, and the other is through contact 15, tongue 16 of relay 17. If locking relay 6 is locked up, then

correcting relay 17 will be operated at the time cam C1 closes its contacts 12 and 13. When contacts 12 and 13 are closed, a circuit is completed from the tongue 31 of relay 6, which is now energized with positive battery, to winding of relay 17, to contacts 12 and 13, and thence to ground. Armatures 16 and 21 of relay 17 will be operated and relay 17 will lock itself up through the following circuit: from tongue 31, winding of relay 17, contact 32 and tongue 16 to ground. Contacts 12 and 13 may now open, but relay 17 will remain energized. The energization of relay 17, in turn, energized corrector magnet CM which placed the pin 33 in the path of starwheel 46 and correction will take place. Shortly after this, cam C2 will open its contacts 22 and 23 which will open the locking circuit of relay 6 which will be de-energized. When the tongue 31 of relay 6 leaves its front contact 30, correcting relay 17 will also be de-energized and this relay in turn will de-energize corrector magnet CM. The length of time during which corrector magnet CM may be energized is the time elapsing between the operation of the contacts controlled by cams C1 and C2. Double corrections cannot occur if the correcting impulses occur after cam C1 is operated and before C2 is operated. At other points of the revolution, however, double correction may occur if necessary.

Referring now to Fig. 2, relay 6 is operated as in Fig. 1, and is provided with a locking circuit extending through contacts 22 and 23 of cam C2 and another locking circuit extending through contact 36 and tongue 37 to ground. Tongue 37 is operated by the armature 25 of the corrector magnet CM. Although locking relay 6 is operated, the corrector magnet CM will not be operated until cam C1 closes its contacts 12 and 13. When these contacts are closed the corrector magnet CM will be operated over the following circuit: ground, battery, contact 30, tongue 31, winding of magnet CM, contacts 12 and 13 to ground.

The armature of the corrector magnet will now be operated and the corrector magnet locked to ground through its winding, tongue 37, contact 38 and contacts 12 and 13. Pin 13 will then engage starwheel 46 and correction will be accomplished. Cam C2 will then open its contacts 22 and 23 thus de-energizing the locking winding of relay 6 and it returns to its normal condition. The disengagement of tongue 31 with contact 30 will in turn cause the deenergization by magnet CM.

What is claimed is:

1. In a telegraph system, the combination with a rotary distributor comprising fixed contact segments, rotating brushes and driving means for said brushes, of a differentially wound relay operable when correction is needed, a corrector magnet conditioned for operation by operation of said relay, means for operating said conditioned magnet to alter the position of said brushes with respect to said driving means, means comprising cams driven by said driving means for limiting the period of operation of said corrector magnet to a fraction of a revolution of said driving means, and circuit means controlled by one of said cams for causing de-energization of said relay while the corrector magnet is operated.

2. In a telegraph system, the combination with a rotary distributor comprising fixed contact segments, rotating brushes and a driving

means for said brushes, of a corrector magnet, means for operating said magnet to alter the position of said brushes with respect to said driving means, a cam driven by said driving means to determine the point in a revolution of said driving means at which said corrector magnet shall operate, and a second cam for determining a point in the same revolution at which said magnet shall be made inoperative. 80

3. In a telegraph system, the combination with a distributor comprising fixed contact segments, rotating brushes and driving means for said brushes, of a corrector magnet for altering the position of said brushes with respect to the driving means therefor, means comprising a differentially wound relay and a relay having a single winding for preparing said corrector magnet for operation, a cam for determining the instant of operation of said magnet in respect to said driving means' cycle, and a second cam for determining the instant during the same revolution of said driving means at which said magnet shall be made inoperative. 85

4. In a synchronous telegraph system, means for maintaining phase relationship comprising a rotary distributor having contact brushes and driving means therefor, means for altering the angular relationship of said brushes with respect to said driving means, and means for assuring that said altering means operate during but a small portion of a cycle of said driving means, said last-mentioned means comprising a cam for making said altering means operative and a second cam for subsequently making said altering means inoperative. 90

5. In a telegraph system, the combination with a rotary distributor comprising fixed contact segments, rotating brushes and driving means for said brushes, of a corrector magnet adapted when operated to cause alteration of the position of said brushes with respect to said driving means, a circuit controlling the operation of said magnet and having at two points therein contacts which must be operated to cause operation of said magnet, a differential relay operable when correction is needed to operate the contacts at one of said points, a cam driven by said driving means to determine the point in a revolution of said driving means at which the contacts at said other point shall operate and thus cause operation of said corrector magnet, and a second cam for determining a point in the same revolution at which said magnet will be made inoperative. 105

6. In a telegraph system, the combination with a distributor comprising fixed contact segments, rotating brushes and driving means for said brushes, a differentially wound relay operable when correction is needed, a second relay prepared for operation by operation of the differential relay, a cam for determining the instant of operation of said second relay in respect to a cycle of said driving means, a corrector magnet operating in response to the operation of said second relay to alter the position of said brushes with respect to said driving means, and a second cam for determining the instant during the same revolution of said driving means at which said relay and said magnet will be made inoperative. 110

7. A phase correction system for telegraph systems comprising a distributor having rotating brushes and a driving means therefor, a differential relay operable when correction is needed, a corrector magnet conditioned for op- 115

eration by operation of said relay, cam controlled means operable at a fixed point in a rotation of said driving means to operate said magnet to effect correction of said brushes with respect to said driving means, a second cam controlled means operable at a second fixed point in said distributor cycle to effect de-energization of said corrector magnet, and circuit means effective when said relay operates in that portion of the distributor cycle lying between said first and second cam controlled means to maintain said relay operated until the second operation of said second cam controlled means following the said operation of said relay.

15 8. A phase correction system according to claim 7 characterized by the provision of circuit means for de-energizing said corrector magnet

upon said second operation of said second cam controlled means.

9. In a synchronous telegraph system, means for maintaining phase relationship comprising a rotary distributor having contact brushes and driving means therefor, means for altering the angular relationship of said brushes with respect to said driving means, means for assuring that said altering means operate during but a small portion of a cycle of said driving means, said last-mentioned means comprising a cam for making said altering means operative, a second cam for subsequently making said means inoperative, and a relay operative whenever a correction is needed and held operated under control of said cams.
